UNITED STATES PATENT OFFICE

FREDERICK R. EAGLESFIELD, OF NILES, MICHIGAN, ASSIGNOR TO THE KAWNEER COMPANY, OF NILES, MICHIGAN, A CORPORATION OF MICHIGAN

JOINING MEANS

Application filed November 22, 1928. Serial No. 321,067.

The present invention relates to joining means especially adapted to be used on double walled furnaces, or other double walled compartments.

5 Among the objects of the invention are to provide a novel means for the joining of the walls in a double walled furnace; further to provide joining means which when used in double walled furnace construction, 10 will be adjustable; further to provide an air space between the walls of the furnace so as to permit ornate coloring of the outer wall or sheet and making them adaptable to be used in living rooms and the like; 15 further to provide an air chamber in the ring itself to prevent the discoloration of the outer shell at the point of contact of the ring and furnace; further to provide rings or bands of maximum simplicity, economy 20 and ease of attachment; and such further objects, advantages and capabilities as will later more fully appear.

My invention further resides in the combination, construction and arrangement of parts illustrated in the accompanying drawings and while I have shown therein a preferred embodiment, it is to be understood that the same is susceptible of modification and change, without departing from the 30 spirit of my invention.

Referring to the drawings:

Fig. 1 is a view in front elevation of a heater or furnace using bands or rings constructed in accordance with the invention;

35 Fig. 2 is a fragmentary view in perspective of a band or ring for connecting the furnace walls.

Fig. 3 is a vertical cross-sectional view through the band or ring on the line 3—3 of 40 Fig. 1.

Figs. 4 and 5 are fragmentary vertical cross sectional views through alternate forms of the band or ring.

Referring now more in particular to the disclosure shown in Figs. 1, 2 and 3 of the drawings, the numeral 1 designates a band or ring, the band or ring comprising an annular head or rib 2 which acts as a support or separating member between the sections 45 of the outer walls 3 and 4; intermediate

flange portions 5, which act as spacers to separate the outer walls 3 and 4 from the inner walls 6 and 7 respectively; and inner flanges 8, the joinder of the inner flanges 8 with the intermediate flange forming 55 shoulders 9 which act as a support or separating member between the sections 6 and 7, as shown in Fig. 3. The rib or head portion 2 of the band 1 will extend outwardly and may be of any desired shape or design, 60 and is provided with shoulders 10. The moulding or bead 12, the inner face of which conforms to the shape of the head, is provided with flanges 11 which abut the outside walls 3 and 4 of the furnace, thereby forming 65 a very compact joint and shoulder. This bead or moulding 12 may be made in sections of any desired length, and of any suitable material so that they may be sprung or forced over the rib or annular head 2, thus forming a very compact joint at the point where the flanges 11 strike or abut the outer walls 3 and 4. This bead or moulding, when sprung or placed over the annular head or rib will also force the ends of the 70 walls 3 and 4 in contact with the shoulders 10 thereby securing a very tight joint. This bead or moulding may also be decorated as desired.

It will also be seen that the inner face of 80 the intermediate flanges is in contact with the outside face of the inner wall. This has been done to prevent the escape of gases, heat or other elements into the chamber between the outer and interior walls.

85 In the alternative form of band or ring, disclosed in Fig. 4, 13 designates a channel shaped annular rib or head which acts as a supporting or separating member between the sections of the outer walls 3 and 4; intermediate flange portions 14, which act as spacers to separate the outer walls 3 and 4 from the inner walls 6 and 7 respectively; bent portions 15; and inner flanges 16, the 90 bent portions 15 at the point of joinder of the intermediate flanges 14 and the inner flanges acting as shoulders which support or separate the sections 6 and 7 of the interior walls of the furnace. As in the embodiment in Fig. 3, this channel shaped annular 95

rib or head extending outwardly, may be covered by a moulding or bead of any shape or design and adapted to butt against the sections of the outer walls 3 and 4 and attached thereto by any suitable means. The bead or moulding may be made of any desired material and may be made in sections of any length and upon which may appear designs or enamel or other coatings applied thereto. As in the embodiment shown in Fig. 3, the inner face of the intermediate flange 14 is in immediate contact with the outer face of sections 6 and 7 of the inner walls thereby forming a very effective joint to prevent the escape of gases or other elements.

In the further alternative form of the annular band or ring disclosed in Fig. 5, 17 refers to the head or rib comprising two outwardly protruding members 18 circumferentially in contact with each other along their entire length, the portions 19 being bent inwardly and angularly into the air chamber between the sections of the walls 3 and 6, and 4 and 7, forming the shoulders 20, which act to support or separate the sections of the outer walls 3 and 4; the portions 20^a being bent inwardly into the inner chamber of the furnace, forming the shoulders 21 which support or separate the sections of the walls 6 and 7 and in their bent and extended portions form the flange shaped portion 22 which provides or forms an air chamber within the ring or band itself. As in the embodiment, disclosed in Fig. 3, the outwardly protruding head 17 may be enclosed with a moulding or bead of any shape or design and adapted to butt against the sections of the outer wall 3 and 4 and attached thereto by any suitable means. It will be seen that the end of the members 19 are in contact with the inner walls and are positioned in such a way as to provide flexible or springing means to 45 keep the sections of the inner walls 6 and 7 in close contact with the shoulders 21, thus forming a very efficient and neat joint at this point and preventing gas or other elements from escaping into the air chamber 50 formed by the space between the outer and inner walls 3 and 6 and 4 and 7, respectively.

While I have herein described and upon the drawings shown a preferred embodiment and alternate forms in my invention, it is to be understood that it is not limited thereto, but comprehends other constructions, details, features and arrangements of parts without departing from the spirit thereof.

Having thus described the invention, I claim:

1. A joining means for a double wall furnace comprising a circumferential piece having an outwardly protruding annular rib 65 and laterally extending intermediate flange

portions, the jointure of said annular rib with said intermediate flange portions forming shoulders to support or separate the outer walls of said furnace, said piece being further provided with interior flange portions, the joinder of which with the intermediate flange portions forming shoulders to support or separate the inner walls of said furnace.

2. A joining means for a double wall furnace or the like, comprising a circumferential piece having an outer rib, the side portions of said piece being bent to form spaced shoulders for receiving the inner and outer walls of said furnace.

3. A joining means for a double wall furnace or the like, comprising a circumferential piece having an outer rib, the sides of said piece being bent to form flanges intermediate of the walls of said furnace and to further provide flanges interiorly of said furnace.

4. A joining means for a double wall furnace or the like, comprising a circumferential piece having an outer rib, the sides of said piece being bent outwardly to provide a shoulder for seating the outer wall of said furnace, the sides of said piece being further bent to provide another shoulder for seating the interior walls of said furnace.

5. A joining means for a double wall furnace or the like, comprising a circumferential piece having an outer rib, the sides of said piece being bent to provide spaced shoulders and flanges, said shoulders adapted to support the walls of said furnace, one of said flanges being interposed between and for separating said walls.

6. A joining means for a double wall furnace or the like, comprising a circumferential piece having an outer rib, the side portions of said piece being bent to provide intermediate and interior flanges having a shoulder therebetween for receiving the inner wall of said furnace, the intermediate flange having a face thereof flush with said wall.

7. A joining means for a double wall furnace or the like, comprising a circumferential piece having an outer rib, the side portions of said piece being bent to provide intermediate and interior flanges, said intermediate flange being interposed between the inner and outer walls of said furnace for separating the same, said intermediate flange having a part in contact with the inner wall for preventing escape of gases from said furnace.

8. A joining means for a double wall furnace or the like, comprising a circumferential piece having an outer rib, the side portions of said piece being bent to provide alternate flange and shoulder portions, the ends of the furnace walls being supported in said shoulders, and a moulding piece on said

rib adapted to contact and bear against the outer wall of said furnace.

9. A joining means for a double wall furnace or the like, comprising a circumferential piece having an outer rib, said piece being bent to provide inner and outer shoulders for receiving the walls of said furnace, and inner and outer flanges, said outer flange adapted to be interposed between and for separating said walls.

10. A joining means for a double wall furnace comprising a circumferential piece having inner flange portions bent toward each other and outwardly to provide a shoulder for the inner wall of said furnace, said outwardly extending portions being bent upon themselves to provide an open seamed rib, said portions bent upon themselves being further bent outwardly to provide a shoulder for the outer wall of said furnace and extending between said walls.

11. A joining means for a double wall furnace, comprising a circumferential piece having side portions bent to provide inner flanges and shoulders for said inner wall of said furnace, said sides extending outwardly and being bent upon themselves to provide an open seamed rib and shoulder for the outer wall of said furnace, said sides being bent outwardly and between said walls and contacting the inner of the same.

12. In a furnace having double walled sections, a joining means comprising a circumferential piece having parts bent to provide a rib between said sections, intermediate flange portions interposed between said walls, and interior flange portions on the interior side of said furnace.

In witness whereof, I hereunto subscribe my name to this specification.

FREDERICK R. EAGLESFIELD.
